SPRING CLIP

Robert F. Smith, Jr., and Paul D. Dale, Rochester, N. Y., assignors to Eastman Kodak Company, Rochester, N. Y., a corporation of New Jersey

Application May 19, 1948, Serial No. 27,866

8 Claims. (Cl. 24—252)

1

The present invention relates to a device which may be attached to the margin of sheet material or to the ends of strips of such material, whereby the materials may be conveniently handled during processing operations or such other treatment to which they may be subjected. More specifically, this invention relates to a photofinishing film clip for holding and supporting photographic film or other sensitized sheet material during the various processing operations.

The present invention is directed to the provision of an improved photofinishing film clip which embodies all the advantages, desired in a device of this type, in an efficient and yet inexpensive device. A photofinishing film clip should positively grip the film to preclude any possibility of the film becoming detached therefrom. This is best accomplished by a device which in fact pierces the film to be gripped. The use of such means, however, is always attended by the possibility that the perforations may be made in the picture area, thereby defacing the film. The film clip embodying the present invention not only provides this positive gripping means, but also limits the degree to which the film may be inserted by the use of stops integrally formed with the base of the clip. Since the clip is often immersed in the processing or washing liquids, it becomes desirable that the clip permit ready drainage of the liquid during the drying period. Otherwise accumulations of liquid, retained by the clip during this drying, will be released upon opening the clip and run down upon the film to streak the latter. The film clip described herein reduces this possibility to a minimum by gripping the edge of the film at spaced points, openings being provided therebetween to facilitate drainage of any pocket of liquid held by the clip.

The present invention may be embodied in a film clip which is used to attach film strips to a supporting bar or in a weighted clip which provides the weight necessary to hold the strips in a vertically suspended position in the processing tank. The manually operable end of the photofinishing film clip, hereinafter described, is adapted to provide means whereby the clip may be securely attached to a supporting bar. The base of the film clip is adapted to mount a heavy element to add to the total weight of the device. This heavy element can be constructed so as to be readily detachable from the base or it can be permanently secured thereto. The clamp, furthermore, is so designed that

2

a minimum of pressure will suffice to open the jaws thereof. All of these features are included in a device which is extremely simple in construction and quite inexpensive to produce.

5 It is, therefore, an object of the present invention to provide an improved photofinishing film clip.

It is a further object of this invention to provide a film clip having improved film-gripping means.

10 It is a still further object of this invention to provide an improved film clip which is adapted to be attached to a supporting structure and, with slight modification, which will serve to hold 15 a film strip in a vertically suspended position.

It is a still further object of this invention to provide an improved film clip which may be readily and easily manipulated, which is simple in construction and which is relatively inexpensive.

20 Other objects and advantages of the invention will become apparent from the following description taken in connection with the accompanying drawing, and it will be understood that 25 many changes may be made in the details of construction and arrangement of parts shown and described without departing from the spirit of the invention as expressed in the accompanying claims. We, therefore, do not wish to be limited to the exact details shown and described 30 as the preferred form only has been shown by way of illustration.

In the drawing:

Fig. 1 is a top view of a photofinishing film 35 clip embodying the present invention;

Fig. 2 is an end view of that film clip showing the film-gripping means;

Fig. 3 is a rear end view of the clip;

Fig. 4 is an enlarged sectional view taken on the line 4—4 of Fig. 1; and

Fig. 5 is an enlarged sectional view taken on the line 5—5 of Fig. 1.

Our photofinishing film clip comprises essentially two elements which make up the jaws of the device. The upper element 10 is a resilient member, preferably formed of metal, one end of which is bent downward to form a series of teeth or projections 11 terminating in the points 12. The opposite end 13 serves as 45 manually-operable means and terminates in a bent-down portion 14, the purpose of which will become later apparent. Intermediate the ends of the resilient member 10, a U-shaped slot 15 cut in the member forms or defines an integral tongue 16. To lend stiffness to the mem-

ber 10 while the tongue 16 and its connection to said member remain essentially resilient a bead or rib 17 is formed about the member 10, as clearly shown in Fig. 1.

The second element of the device is the base unit 18 which is preferably molded of plastic. Projecting means, such as a pair of studs 19 integrally formed with the base, provide attaching means for securing the tongue 16 of the element 10 to the base unit. Screws 20, threaded into the studs 19, fasten the resilient tongue to the base unit, although obviously any equivalent fastening means may be employed. To enhance the resiliency of the tongue 16 and augment the gripping action of the device, a helper spring 21 overlies the tongue and is secured to the element 10 and the base 18 by the means 20 which holds the latter two elements together, as already described. This helper spring, a leaf spring, exerts downward pressure upon the forward half of the resilient member 10, as illustrated in Fig. 5. A pair of integral projections upon the base unit 18 provide a series of fulcrum points 22 upon which the member 10 may be pivoted or rocked to open the clip when pressure is exerted upon the manually-operable means 13. These integral projections also provide stops 23 which restrict the amount of film 24 which may be inserted into the photofinishing clip. This substantially precludes the possibility of the film clip engaging the film or film strip beyond the marginal edge whereby the points 12 might pierce the picture area, thereby damaging the film.

The base unit 18 is further provided at its forward end with recessed or tubular bosses 25, each of which is adapted to receive a single point 12. This permits the latter to readily perforate the engaged film, thereby insuring positive gripping. The tops of the bosses engage the projections 11, mounting the points, restricting the depth of penetration and providing a firm clamping action upon the film which can only be released by pressure upon the manually-operable means 13. The configuration of the projections 11 and bosses 25 is such that, when the film is suspended by the clip from a supporting bar to dry, the various processing and washing liquids are readily drained from the clip. No pockets of liquid are thus retained which, upon release of the clip, may run down upon the film to streak the surface. This end configuration of the film clip is best noted in Fig. 2.

As described above, one end of the resilient member 10 terminates in the bent-down portion 14. This portion projects slightly into a recess 26 formed in one end of the base unit, as clearly seen in Figs. 1, 3 and 5. The base 18, the resilient element 10, and the turned-down end 14 thereof thus cooperate to form a loop by means of which the film clip and the attached film may be suspended from a bar or similar supporting structure. This particular arrangement allows the rear end 13 of the member 10 to be depressed to open the clamp, and yet permits the clip to be suspended from a support without the danger of it being accidentally detached therefrom.

Since a film strip suspended in a treating bath will ordinarily not hang properly but will tend to curl and wind upon itself, it is desirable to secure a weight to the bottom of the strip. The film clip embodying the present invention is also adapted to be used for this purpose. The base unit 18 is provided with apertures 27 and 28 which are adapted to receive the bosses 29 and

30, respectively, integrally formed on the weight 31. The latter element, which is preferably formed of a heavy metal, gives the clip assembly sufficient weight whereby, when attached to the lower end of a film strip, the strip will be vertically and properly suspended. The ends of the bosses 29 and 30 may be upset in the apertures 27 and 28 to fasten the weight 31 permanently to the base unit 18, although obviously other means and methods may be employed to permanently secure these two elements together. Alternately, the bosses may be secured in the respective apertures by means of a friction or push fit, the clip base and weight being readily separable by inserting a sharp instrument between the adjacent faces of the base and weight. The aperture 28 is aligned with a hole 32 of similar diameter provided in the member 10. When the film clip is used independently of the weight 31, the holes 28 and 32 may be employed as means by which the clips may be threaded upon a supporting bar. Thus, two different means are provided for attaching a series of the described film clips to a supporting structure, one permitting the strips to be supported in planar relationship, the other in non-planar parallel relationship.

The materials, both metal and plastic, of which the various elements of the above-described film clip are composed are selected from those which are not adversely affected by the chemicals employed in the various processing operations to which the film clips will be exposed.

From the foregoing, it will be apparent that we have provided means for obtaining all the objects and advantages of this invention.

What we claim and desire to secure by Letters Patent of the United States is:

1. A film clip comprising a base, a resilient member having teeth offset from one end thereof and manually-operable means at the other end, a U-shaped slot intermediate the ends of said member defining a substantially flat integral tongue, and means securing the free end of said tongue to the base whereby the teeth of said member are normally held in engagement with the base by the resilience of the tongue.

2. A film clip comprising a base unit and a resilient member, said resilient member having teeth at one end thereof and an offset projection at the other end, a U-shaped slot intermediate the ends of the member forming an integral tongue therein, said base unit having an integral stud intermediate its ends and a recess in one end thereof, said tongue being secured to the stud whereby the offset projection of the member is received in the recess and the teeth of the member are normally held in engagement with the base unit by the resilience of the tongue.

3. A film clip comprising a base unit and a resilient member, said resilient member having film-engaging means at one end, manually-operable means at the other end, and a resilient tongue integrally secured intermediate the ends of said member, said base unit having a stud and a projection on one face thereof intermediate the ends of the base unit, said tongue being secured to the stud whereby the film-engaging means of the member are normally held in engagement with the base unit by the resilience of the tongue and may be disengaged therefrom by exerting pressure on said manually-operable means to pivot said member about said projection.

4. A film clip comprising a base unit and a resilient member, said resilient member having

teeth at one end and manually-operable means at the other end, a U-shaped slot intermediate the ends of the member forming an integral tongue therein, said base unit having an integral stud and a pair of projections on one face thereof intermediate the ends of the base unit, said tongue being secured to the stud whereby the teeth of the member are normally held in engagement with the base unit by the resilience of the tongue and may be disengaged therefrom by exerting pressure on said manually-operable means to rock said member about said pair of projections.

5. A film clip comprising a base unit and a resilient member, said resilient member having teeth at one end and manually-operable means at the other end, a U-shaped slot intermediate the ends of said member defining an integral tongue therein, said base unit having a stud intermediate its ends, a leaf spring, said tongue and leaf spring being secured to the stud whereby the teeth of the member are normally held in engagement with the base unit by the combined resilient urging of the tongue and the leaf spring.

6. A film clip comprising a base unit and a resilient member, said resilient member having teeth at one end and an offset projection at the other end, a tongue integrally formed intermediate the ends of said member, said base unit having an integral stud intermediate its ends and a recess in one end thereof, a leaf spring, said tongue and leaf spring being secured to the stud whereby the offset projection is received in the recess and the teeth of the member are normally held in engagement with the base unit by the combined resilient urging of the tongue and the leaf spring.

7. A film clip comprising a base unit and a resilient member, said resilient member having teeth at one end and manually-operable means at the other end, a tongue integrally formed in-

termediate the ends of said member, said base unit having projecting means and a fulcrum on one face thereof intermediate the ends of the base unit, a helper spring, said tongue and helper spring being secured to the projecting means whereby said member may be rocked about the fulcrum, the teeth of the member being normally held in engagement with the base unit by the combined resilient urging of the tongue and the helper spring.

8. A film clip comprising a base unit and a resilient member, said resilient member having film-engaging means at one end and manually-operable means at the other end, a tongue integrally formed intermediate the ends of said member, said base unit having a projection intermediate its ends, a helper spring, said helper spring and tongue being attached in overlapping relation to the base unit whereby said member may be rocked about said projection, the film-engaging means of the member being normally held in engagement with the base unit by the combined resilient urging of the tongue and helper spring.
